US00D944543S

(12) **United States Design Patent** (10) **Patent No.:** **US D944,543 S**
(45) **Date of Patent:** **** Mar. 1, 2022**

(54) **HANGER**

- (71) Applicant: **TARGET BRANDS, INC.**, Minneapolis, MN (US)
- (72) Inventors: **Laurie Losness**, Coon Rapids, MN (US); **Richard P. Riedel**, Blaine, MN (US); **Terrence J. Hornsby, Jr.**, Minneapolis, MN (US)
- (73) Assignee: **TARGET BRANDS, INC.**, Minneapolis, MN (US)
- (**) Term: **15 Years**
- (21) Appl. No.: **29/813,572**
- (22) Filed: **Oct. 29, 2021**

Related U.S. Application Data

- (62) Division of application No. 29/712,577, filed on Nov. 8, 2019, now Pat. No. Des. 936,979.
- (51) **LOC (13) Cl.** **06-08**
U.S. Cl.
USPC **D6/318**; D6/315

“Velvet Flocked Hanger”, printed from www.dhgate.com/product/flocked-hanger-with-good-quality-druable/138480211.html, publicly available at least as early as Jan. 18, 2017 (3 pages).

Primary Examiner — Lauren R Calve

(74) *Attorney, Agent, or Firm* — JoAnn M. Seaton; Griffiths & Seaton PLLC

(57) **CLAIM**

The ornamental design for a hanger, as shown and described.

DESCRIPTION

FIG. 1 is a front, top perspective view of a hanger showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The features shown in broken lines are portions of the hanger forming no part of the claimed design.

1 Claim, 4 Drawing Sheets
